E. M. SALERNI

CONDENSER

Filed Oct. 31, 1925

Inv. No. 1,680,641
Eduardo M. Salerni
by Cushman Bryant & Kirby, Atty.

UNITED STATES PATENT OFFICE.

EDOARDO MICHELE SALERNI, OF PARIS, FRANCE, ASSIGNOR TO E. M. S. INDUSTRIAL PROCESSES LIMITED, OF LONDON, ENGLAND, A CORPORATION OF ENGLAND.

CONDENSER.

Application filed October 31, 1925, Serial No. 66,053, and in Great Britain November 10, 1924.

This invention relates to heat interchange apparatus of the kind in which the medium undergoing treatment is caused to flow in a sinuous or tortuous path around a series of 5 plates or baffles, and has for its chief object the provision of an improved form of apparatus of this character having provided a relatively large heat interchange area or surface and which is constructed of a relatively few standardized or interchangeable parts so as to permit the apparatus to be 10 easily and quickly assembled or dismantled for replacements or repairs.

The invention may be employed in connection with apparatus for heating, cooling or condensing fluids, and is particularly intended for use in condensing oil gases or vapours.

Heretofore the aforesaid plates or baffles 20 around which the medium flows have been disposed within circular tubes, and such tubes, in cases where they are superimposed or arranged side by side, and when employed for the purpose of condensing fluids, possess 25 the disadvantage that the condensate after treatment drains off at the end of each tube, and has therefore to be collected at a large number of points. This drawback is overcome in the present invention by causing 30 the medium to flow in a sinuous or tortuous path around baffle plates which are of elongated form and are removably disposed within a tubular member or conduit or rectangular or flattened construction, that is 35 to say, a conduit having a height which is large in relation to its width when it is disposed within an outer casing or mounted between tube sheets.

In order that the said invention may be 40 clearly understood and readily carried into effect, the same will now be described more fully with reference to the accompanying drawings in which:—

Figure 1 is a part sectional elevation, the 45 section being taken on the line 1—1 of Figure 2 showing one embodiment of the invention.

Figure 2 is a part sectional plan view of Figure 1.

Figure 3 is a sectional end view of the line 50 3—3 of Figure 2, and

Figure 4 is a part sectional end view of Figure 1.

Figures 5 and 6 are partly diagrammatic 55 sectional plan views showing a further embodiment of the invention.

e is an outer rectangular casing containing a series of rectangular or flattened tubular members or conduits *e'*, *e''* extending longitudinally therethrough and having their ends secured in tube sheets *a* and *b* so as to prevent any possibility of the fluid passing through the tubular members or conduits mixing with that which passes around the conduits. The conduits *e'*, *e''* are formed or arranged so that their height is large in relation to their width, and are preferably disposed within the casing *e* side by side in spaced relation and in parallel rows. Each conduit contains a series of baffle plates *e²*, *e³* of angular construction disposed in staggered relationship to one another and extending substantially from the top to the bottom of the conduit. The baffle plates are mounted upon rods *e⁴*, *e⁵* disposed longitudinally of and extending beyond the ends of the conduits, each pair of rods being connected by a bar *e⁶*. The baffle plates are preferably L-shaped and are arranged within the conduits so that one edge of each angle plate bears against one wall of the conduit, while the other edge projects towards the centre thereof and is connected to the rods *e⁸*, *e⁹*, so that an entire set of baffle plates can simultaneously be withdrawn from the apparatus for cleaning or other purposes.

Suitable openings *e^{5x}*, *e^{5x}* are provided adjacent opposite ends of the outer casing *e* for admitting and withdrawing fluid from the space around the conduit *e*. For the circulation of the fluid which is caused to pass through the conduits *e'* the tube sheet *a* is connected to a casing *e⁷* provided with openings *e⁶* and *e⁹*, while the tube sheet *b* is connected to another casing *d* provided with opening *e¹⁰* and *e¹¹*.

The use of conduits of flattened construction instead of circular casings or tubes, has the advantage that a large number of such conduits can be located within an outer surrounding casing in a very compact manner, while the use of long plates or baffles disposed within said conduits has the further advantage that in the case of a condenser the condensate flows down the plates of 105 baffles to the bottom of each conduit so that

it can conveniently be removed from one end thereof, or at one or more points along the lower side of the casing.

It will be observed that the apparatus is 5 of simple construction and is formed of a relatively few standardised or interchangeable parts so as to facilitate assembly or dismantling for replacements or repairs.

When employing the apparatus illustrated 10 for the condensation of oil gases or vapours a cooling medium is admitted to spaces around the conduits e' through the opening e^5 and withdrawn through the opening e^{10} . The gases or vapours which are to be condensed are admitted to the outer casing through an opening e^6 and before entering the aforesaid conduits e' , e' they pass through the chamber e^7 located at the entrance thereto. This chamber contains a 15 number of depending baffle plates e^8 , e^8 and on the gases striking the said baffles e^8 , e^8 the heavier oils are precipitated and can be led away from the chamber e^7 through the opening e^9 . The uncondensed vapours 20 thereafter enter the conduits e' , e' and owing to the arrangement of the baffle plates e^2 the gases are compelled to follow a sinuous path in passing from end to end thereof. The condensed oils leave the apparatus 25 through the opening e^{10} while the uncondensed vapours leave the apparatus through the opening e^{11} . The conduits e' , e' may, if desired, be divided into sections by means of baffle plates such as e^{12} which extend from 30 side to side thereof and project upwardly from the base thereof so as to leave at the top a space f which allows the vapours to pass but separates the condensate in one zone from the condensate in other zones, so 35 that the liquid oils can be collected separately from each of the same zones. The apparatus is provided at one end with a cleaning door e^{13} , and by opening the same and withdrawing by means of the rods e^4 the 40 angle plates of any one conduit the same can readily be cleaned without disturbing the other conduits. Referring to Figures 5 and 45 6, F is a conduit of flattened, construction similar to one of the rectangular conduits e' shown at Figures 1 to 4 and a plurality of which may replace the conduits e' within the outer casing e , the conduit F containing a number of channel or U shaped members 50 F' , F' , which may either be loosely located 55 within the conduit or which may be riveted together as shown at F^2 . The U-shaped members F' , F' , are staggered relatively to one another as shown and are mounted upon a rod G of oblong cross section, the rod being passed through oval, oblong or elongated slots F^3 , F^3 , in each of the baffle plates F' . By turning the rod G into the position 60 shown at Figure 5 the channel shaped baffles F are tightly pressed against the casing F , thus serving to produce an efficient heat in- 65

terchange between the medium undergoing treatment and the heating or cooling medium applied externally to the casing F . When, however, it is desired to remove the baffles for cleaning or other purposes the 70 rod G is turned into the position shown at Figure 6 thus bringing the members F' out of contact with the walls of the casing F and allowing the same to be removed for 75 cleaning and other purposes.

Although the various features of the invention have been more particularly described in connection with the treatment of vapours derived from the distillation of carbonaceous materials, it is to be understood that, where applicable, they may be employed for the treatment of other gases, 80 vapours or materials.

What I claim and desire to secure by Letters Patent of the United States is:— 85

1. Heat interchange apparatus comprising an outer casing, a plurality of elongated conduits of flattened construction disposed within the casing and spaced from each other and from the walls of the outer casing, and means in said conduits for causing a medium admitted thereto to pursue a sinuous path from end to end thereof. 90

2. Heat interchange apparatus comprising an outer casing, a plurality of elongated conduits of flattened construction disposed within the casing and spaced from each other and from the walls of the outer casing, and a plurality of baffle plates extending substantially from the top to the bottom of 100 each of the conduits. 105

3. Heat interchange apparatus comprising an outer casing, a plurality of elongated conduits of flattened construction disposed within the casing and spaced from each other and from the walls of the outer casing, and a plurality of removable baffle plates of angular construction extending substantially from the top to the bottom of each of 110 the conduits. 115

4. Heat interchange apparatus comprising an outer casing, a plurality of elongated conduits of flattened construction disposed within the casing and spaced from each other and from the walls of the outer casing, and a plurality of baffle plates arranged in each of the conduits, said baffle plates being mounted upon rods in such a manner that the baffle plates in any one conduit can be withdrawn from the apparatus without disturbing the baffle plates in the other conduits. 120

5. Heat interchange apparatus comprising an outer casing, a plurality of elongated conduits of flattened construction disposed within the casing and spaced from each other and from the walls of the outer casing, and a plurality of baffle plates arranged in each of the conduits, the baffles contacting alternately with the opposite inner walls of 125 130

each conduit so as to facilitate heat interchange and to cause a medium admitted thereto to pursue a sinuous path from end to end thereof.

- 5 6. Heat exchange apparatus comprising an outer casing, a plurality of elongated conduits of flattened construction disposed within the casing, each conduit containing a plurality of baffles constituted by angle plates, one edge of each angle plate being attached to a member so that a set of baffles can simultaneously be withdrawn from the apparatus for cleaning or other purposes and another edge of each plate being arranged to bear against a wall of the conduit in which it is located so as to facilitate heat interchange.
- 10 7. Heat interchange apparatus comprising an outer casing, a plurality of elongated conduits of flattened construction disposed
- 15
- 20

within the casing and spaced from each other and from the walls of the outer casing, and a plurality of L-shaped baffle plates arranged in each of the conduits so as to extend over substantially the full height of 25 the conduit, such baffle plates being spaced apart longitudinally of the conduits and secured to means whereby they may be readily removed therefrom when desired.

8. Heat interchange apparatus comprising an outer casing, a plurality of elongated conduits of flattened construction disposed within the casing and spaced from each other and from the walls of the outer casing, a plurality of baffle plates of angular construction arranged in each of the conduits and means for moving the baffle plates into and out of contact with the inner walls of the conduits. 30 35

EDOARDO MICHELE SALERNI.
